UNITED STATES PATENT OFFICE

GRADY R. SWOPE, OF ST. PETERSBURG, FLORIDA

ARTIFICIAL GOLF-COURSE COVERING

Substitute for application Serial No. 421,049, filed January 15, 1930. This application filed May 8, 1930.
Serial No. 450,798.

The present invention relates to an improved artificial covering or matting for indoor and outdoor golf courses, and is a substitute for allowed application Serial No. 5 421,049, filed Jan. 15, 1930.

In localities where it is difficult for grass to grow, because of climatic or soil conditions, golf courses in such places have their putting greens covered with artificial substances to simulate, as closely as possible, the conditions met with when playing over a grass green. Moreover, due to the increasing popularity of golf and the large number of players using the links, it is quite difficult to 10 keep the grass on the putting green in proper playing condition, and consequently it is often necessary to employ an artificial green which will not become worn under constant usage.

20 The artificial greens heretofore employed have been usually composed of short fibers of material held together by a suitable binder. The main difficulty with these greens has been that the fibers soon become loose, and 25 when walked on leave indentations which constantly require them to be leveled and rolled.

An essential object of the present invention is to provide an artificial green composed of 30 cut fibers of a substance which, when the fibers are mixed and secured by a viscous binder, forms a matted surface which, in properties and characteristics, very closely simulates the turf used on natural greens.

35 A further object consists in using feathers as the main ingredients in the construction of the artificial green. Preferably, the feathers are cut into short pieces and mixed together, and then secured by a suitable 40 binder.

Due to the tenacious and flexible character of the barbs, the cut pieces tend to cling or adhere to one another, so that in its final form, the matted surface constitutes a homogeneous mass, the parts of which are so intertwined as to be capable of resisting any force or pressure tending to separate them. The intertwined barbs provide a soft surface 45 resembling, in many respects, an ordinary grass green and suitable treatment thereof as

by including another substance, such as sand, sawdust or other divided material will give weight to the mass. Moreover, it will ordinarily be desired to employ a suitable binder.

Preferably the feathers are comminuted or 55 cut so that the particles are relatively small, although if extremely small feathers are used this would be an equivalent of comminution, and the invention as disclosed and claimed with respect to comminution or cutting of 60 the feathers is to be so interpreted.

If desired, small pieces of the stems may be retained with some barbs attached thereto, but, if retained, the stem pieces must be extremely small, since large pieces would form 65 surface projections of undesirable character and interfere with the movement of a ball. However, equally good, if not better results are obtained when the stem pieces are substantially eliminated.

70 It has been found that an artificial green constructed in accordance with the present invention possesses characteristics and features very closely simulating a turf "putting green", since the exposed barbs tend to assume 75 positions similar to short blades of grass and offer a certain degree of resistance to the ball when moved thereover.

It has been found that an artificial green composed of feathers will not rot as quickly 80 as other substances, while the green coloring mixed with the binder does not easily lose its shade when subject to the elements. As feathers may be obtained in all parts of the country, this artificial green may be very 85 economically produced, and its wearing qualities are materially enhanced due to the tenacious character of the barbs which have a tendency to felt and cling together and will not tear or separate under ordinary use.

90 A further object consists in a new and novel process of constructing an artificial green.

Another object of the invention consists in adding sawdust to the feathers so as to increase the bulk of the matted surface, and 95 also lessen the cost of production. Additionally, sand may be added to give weight to the mass.

Further objects and advantages of the invention will become apparent from the fol- 100

lowing description when taken in conjunction with the accompanying claims.

Referring to the drawings in which is disclosed several preferred embodiments of the invention:

5 Figure 1 is a sectional view of the ground around a putting green with my artificial covering applied thereto.

10 Figure 2 is an enlarged detail view showing the intertwining relation existing between the barbs of the feathers, certain stem particles being retained in the form illustrated.

15 Referring to the drawings, in which like numerals indicate like parts in the several views, 10 denotes the ground surrounding one of the holes 11 of a golf course, which is commonly referred to as the "putting green".

20 In order that the putting green in localities where it is difficult to grow grass may simulate as closely as possible the conditions existing on a grass golf course, I have provided an artificial covering or matting surface 12 which is preferably composed of cut feathers that are first graded according to 25 size, and then reduced to small pieces. The cut feathers 13 are then treated as by mixing with a suitable liquid substance such as oil or the like, so as to give weight to the mass, said substance also acting as a viscous binder. The 30 oil may first be mixed with a green or other coloring matter and then mixed with the feathers, so as to form a composite mass capable of being readily applied to the ground surface. The mixture is then ready to be 35 laid on the green and when rolled out, presents a surface very closely approximating in characteristics a grass green. Refuse oil from cylinder crank cases has been found to be very satisfactory and gives the desired 40 weight to the mixture. Moreover, oil-paint or tar may also be used as a binder.

45 In order to give bulk and weight to the mass and also reduce the cost of producing the artificial green, a divided substance, such as sawdust or sand, or both, may be added to the mixture in varying proportions. I have found a mixture of two portions of sawdust to one of feathers to be very satisfactory and efficient in use. The sawdust, in addition to 50 giving bulk to the mass, also tends to smooth out to a certain degree the exposed surface and fill up any interstices that might otherwise be formed therein. Sand may be added so as to give weight to the mass.

55 An artificial covering composed of the following ingredients by volume has been found to be very satisfactory: three portions of feathers, six portions of sawdust, about one portion of sand and one-fifth portion of oil.

60 Of course, the ingredients may be mixed in varying proportions as determined by the best working conditions.

65 Feathers have been found to be admirably suited for making artificial putting greens, because of the fact that when the feathers

are cut into short pieces, the barbs 14 (Fig. 2) intertwine and due to the tenacious and adhering qualities of the barbs, the fibers are not easily separated. This feature is diagrammatically shown in Figure 2, in which figure the loose or cut barbs which are free from the stems, are not shown, so as to more clearly disclose how the stems, if retained, and barbs tend to cling or adhere when formed into a matted surface. It will be understood that the covering includes barbs which are free from the stem pieces, as well as the stem attached barbs of Figure 2.

An important and desirable feature of the invention resides in the fact that, in its final form, my artificial covering, when rolled, assumes a shape that allows the exposed barbs to protrude or project upwardly to retard the movement of a ball thereover, and thus very closely simulates the turf of a grass green. Moreover, any retained short stem pieces 15 are of flexible and yieldable character, and may be bent to assume various shapes, but are not easily broken. Even when transversely cracked the parts remain 90 jointed and will not separate. Consequently, the composite mass when walked on or distorted by a ball has a tendency to immediately return to its normal shape when the pressure is released, and does not leave imprints or 95 indentations therein. While my artificial covering is particularly adapted for use on the "putting green", it is quite obvious that it may also be efficiently employed as a covering on the fairway or any other parts of 100 both indoor and outdoor golf courses, croquet, tennis courts and other games, and the term "golf courses" as used throughout the specification and claims is to be so interpreted.

105 The term "feathers", as used throughout the specification and claims is intended to cover either the complete feather, i. e., stem and barb, or any portion thereof. The terms "communited", "cut" or "divided", as applied to "feathers" is intended to cover not merely large feathers reduced to appropriate size, as described, but also very small feathers which may, in their original state, be sufficiently small to permit their use without sub-division.

110 It is to be understood that the forms of the invention herewith shown and described is merely illustrative of a preferred embodiment, and that the artificial covering and method of producing the same may assume such other forms as fall within the purview of one skilled in the art without departing from the spirit of the invention and the scope 115 of the appended claims.

120 I claim:

1. An artificial covering for golf courses comprising a matted surface composed of intertwined feathers, and a binder for the mixture.

2. An artificial covering for golf courses comprising a matted surface composed of comminuted intertwined feathers, and a binder for the mixture. 70
5. An artificial covering for golf courses comprising a matted surface composed of intertwined feather barbs detached from their stems, and a binder for the mixture. 75
10. An artificial covering for golf courses comprising a matted surface composed of intertwined feathers, a finely divided substance added to the feathers to give weight to the mass, and a binder for the mixture. 80
15. An artificial covering for golf courses comprising a matted surface composed of feather barbs detached from their stems and intertwined the stems being substantially removed, a finely divided substance added to the feathers to give weight to the mass, and a binder for the mixture. 85
20. An artificial covering for golf courses comprising a matted surface composed of feathers treated to give additional weight thereto and having their barbs intertwined. 90
25. An artificial covering for golf courses comprising a matted surface composed of feathers cut and mixed so that their barbs are intertwined, sand mixed with said feathers, and a binder securing the mixture together. 95
30. An artificial covering for golf courses comprising a matted surface composed of feathers cut and mixed so that their barbs are detached from their stems and intertwined, sand mixed with said feathers, and a binder securing the mixture together. 100
35. An artificial covering for golf courses comprising a matted surface composed of feathers cut and mixed so that their barbs are intertwined, a finely divided substance mixed with said feathers, and a binder securing the mixture together. 105
40. An artificial covering for golf courses comprising a matted surface composed of feathers cut and mixed so that their barbs are detached from their stems and intertwined the stems being substantially removed, sand mixed with said feathers, and a binder securing the mixture together. 110
45. An artificial covering for golf courses comprising a matted surface composed of cut feathers connected by their barbs, sawdust mixed with said feathers, sand added to said mixture, and a binder securing the mixture together. 115
50. An artificial covering for golf courses comprising a mass composed of cut feathers mixed so that their barbs are intertwined, whereby the mass tends to resist pressure causing the separation of the feathers, and a colored oil binder securing the feathers together. 120
55. The method of making an artificial cover for golf courses which consists in cutting feathers into small pieces, mixing the 125
60. 130

feathers with a liquid binder so as to cause the barbs to be intertwined, adding a finely divided substance to the mixture, and rolling the mixture over a surface to which it is applied.

In testimony whereof I have hereunto set my hand.

GRADY R. SWOPE.
